UNITED STATES PATENT OFFICE

WALTER S. CLEMENCE, OF BATTLE CREEK, MICHIGAN

DESIGN FOR A CHILD'S CHAIR

Application filed April 12, 1930. Serial No. 35,234. Term of patent 14 years.

To all whom it may concern:

Be it known that I, WALTER S. CLEMENCE, a citizen of the United States, residing at Battle Creek, in the county of Calhoun and State of Michigan, have invented a new, original, and ornamental Design for a Child's Chair, of which the following is a specification, reference being had to the accompanying drawings, forming a part thereof, in which—

Fig. 1, is a front view of a child's chair, showing my new design.

Fig. 2, is a perspective view, and

Fig. 3, is a side view.

I claim:

The ornamental design for a child's chair, as shown.

WALTER S. CLEMENCE.
